CLAIM

The ornamental design for an electric motor, as shown and described.

DESCRIPTION

FIG. 1 is a front side view of an electric motor showing the present design;

FIG. 2 is a first perspective top view thereof;

FIG. 3 is a perspective bottom view thereof;

FIG. 4 is a bottom view thereof;

FIG. 5 is a second perspective top view thereof;

FIG. 6 is a top view thereof;

FIG. 7 is a back side view thereof; and,

FIG. 8 is a right side view thereof.

The broken lines shown depict the portions of the electric motor that form no part of the claimed design.
